SANDER NOZZLE ASSEMBLY

Filed Nov. 12, 1946

UNITED STATES PATENT OFFICE

2,577,009

SANDER NOZZLE ASSEMBLY

Virgil L. Frantz, Roanoke, Va.

Application November 12, 1946, Serial No. 709,225

11 Claims. (Cl. 291—11)

1

This invention relates to sanders for locomotives and the like and particularly to sander nozzle assemblies.

An object of the invention is to provide an improved sander nozzle assembly by which the sander nozzle can be connected directly to the air pressure line without the use of external couplings.

Another object of the invention is to provide an improved nozzle assembly having means enabling the nozzle to be adjusted longitudinally relative to the body of the sand trap without disconnecting the air line from the nozzle.

An additional object of the invention is to provide an improved nozzle assembly having means for preventing sand from contacting and impairing the threaded connections of the assembly.

A further object of the invention is to provide an improved nozzle assembly of simple and rugged construction and long useful life.

Other objects and advantages of the invention will appear hereinafter in the detailed description, be particularly pointed out in the appended claims and illustrated in the accompanying drawings, in which:

Fig. 1 is a vertical sectional view of a sand trap to which has been applied the improved nozzle assembly, and

Fig. 2 is an isometric view of the sealing ring employed in the assembly.

Referring now in detail to the drawings in which like reference characters designate like parts, the improved nozzle assembly, for purposes of illustration, has been shown applied to a sand trap. The illustrated sand trap is of the type employed on locomotives and the like and has a body 1 which is adapted to be formed as an integral casting. The body is preferably an L-shaped hollow member provided at its upper end with a sand inlet port 2 which is connected by a coupling 3 of any suitable type to the usual sand dome, not shown. The body is also provided with a clean-out port 4, normally closed, and one or more sand outlet ports 5 through which it is suitably connected to a sand outlet line, not shown, leading to the rails.

The present invention relates particularly to the means by which an air blast is admitted to the hollow interior of the sand trap body to force sand through one of the sand outlet ports 5 when the sand trap is actuated. This means, termed hereinafter the sander nozzle assembly, is adapted to introduce a blast of air into the body 1 through a nozzle or air inlet opening 6. This

2

opening is positioned below the sand inlet port 2 and directed toward the sand outlet portion of the body, preferably at an inclination below the longitudinal axis of the lower leg 7 of the body. Encircling the outer end of the nozzle opening 6 and preferably integral with the body 1 is a nozzle seat formed as a boss or circular flange 8. The flange is provided with an annular opening 8a defined by its cylindrical inner wall, the latter being coaxial with the opening 6. Adapted to be introduced into the body 1 through the nozzle seat opening 8a and the nozzle opening 6 and to be attached to the body through the nozzle seat 8 is a nozzle 9. While the nozzle 9 may be formed as an integral member its forward portion or tip which normally extends into the interior of the body 1 is preferably a pipe or tube 10 of cylindrical shape, removably attached to the main or body portion of the nozzle 9 as by threads 11. The body portion of the nozzle 9 adjacent the tube is comprised of a substantially cylindrical shank or seating portion 12 of greater outside diameter than the tube 10 and having a central cylindrical passage 13 of the same diameter as and coaxial with the interior of the tube 10. Outwardly of the shank the nozzle 9 is enlarged to provide a head 14 through which the nozzle is connected to a suitable air pressure line, not shown. As will appear hereinafter, the head 14 is adapted to be connected directly to the air pressure line. For this purpose the head 14 is provided with a tapered threaded opening 15 for receiving the end of the air line, the opening 15 being coaxial with and connected to the central passage 13 in the shank 12.

The nozzle 9 is connected to the body 1 through a collar or nut 16 having an outer portion or shoulder 17, which is adapted to abut the outer face of the boss 8, and a stem or inner portion 18 of reduced cross-section which is adapted to be inserted in the nozzle seat opening 8a. The outer face of the stem 18 of the collar is cylindrical and of substantially the same diameter as the cylindrical seat opening 8a, thus enabling the collar to be slidably seated in and freely rotated relative to the boss 8.

For locking the collar 16 against axial or longitudinal movement relative to the boss 8 there is provided a split snap, resilient or spring ring 19 which is adapted to seat in an outwardly facing circumferential groove or slot 20 formed in the stem 18 of the collar intermediate its ends. As shown, the groove is preferably rectangular in cross-section and of a depth substantially equal to the corresponding dimension

of the ring. Inwardly of the outer face of the boss 8, the wall of the opening 8a is slotted to provide an annular inwardly facing groove 21 preferably rectangular in cross-section and of less depth than the depth of the ring 19. The groove 21 is so spaced relative to the outer face of the boss that it aligns with and confronts the groove 20 in the stem when the collar is fully seated, the shoulder 17 then abutting the outer face of the boss. To enable the ring to serve as an interlock between the grooves and at the same time to permit the collar to be inserted in the seat opening 8a, the ring in free condition is of substantially greater outside diameter than the stem 18, enabling it to press against the bottom wall of the groove 21, and when compressed by bringing the split ends toward each other can be confined entirely within the groove 20.

With the above construction, the stem 18, with the ring seated in the groove 20, can be inserted in the seat opening 8 by contracting the ring, the ring thereafter being confined in the groove by the wall of the opening until it reaches the groove 21. The ring then expands and, by overlapping the joint between the collar and the boss, locks the collar against outward axial movement. To insure close fit between the ring and the groove as well as to provide frictional resistance against accidental rotation of the collar the ring is preferably radially corrugated as shown in Figure 2. Although the locking ring can be employed to lock the collar against axial movement in either direction, in the illustrated embodiment it functions only as a stop against outward movement, inward movement being prevented by the abutment of the shoulder 17 of the collar with the outer face of the boss 8.

To enable rotation of the collar 16 to vary the longitudinal position of the nozzle 9 relative to the trap body 1, the confronting faces of the stem 12 of the nozzle and the collar are desirably provided with interlocking position-adjusting threads 22. To connect the nozzle to the air pressure line or pipe, the latter is introduced into the tapered threaded opening 15 in the nozzle and the nozzle is then turned either with or independently of the collar to force the threaded end of the pipe into the opening, thus sealing the connection between the pipe and the nozzle. The position of the nozzle relative to the trap body can then be altered by holding the head of the nozzle against rotative movement and rotating the collar in the direction required to either withdraw or project the nozzle further into the body, as desired. To facilitate attachment of the sand trap, the nozzle will ordinarily be adjusted such that it will occupy its proper position relative to the body when the head of the nozzle is in engagement with the outer face of the collar. Once the nozzle is adjusted, frictional engagement between the corrugated ring 19 and the collar of the boss will prevent change of position of the nozzle by accidental rotation of the collar.

An important feature of this invention is the means by which sand is prevented from seeping into and wearing the adjusting threads 22 on the collar and the nozzle. To reduce seepage through the nozzle opening to a minimum the opening is tapered toward the interior of the body 1 and adapted to receive a tapered sleeve or hollow plug 23, which is designed to fit tightly into the opening. The bore of the sleeve is cylindrical and of substantially the same diameter as the outside of the nozzle projection or pipe 10, the sleeve thus

serving as a guide for centering the nozzle, as well as a seal. Both sleeve and pipe are preferably made of brass or like material to eliminate corrosion and consequent binding or sticking in use.

Outwardly of the opening 6 there is provided in the boss 8 a cylindrical recess 24 of greater diameter than the collar seat opening 8a. At its bottom, this recess is provided with a drain or outlet 25 extending through to the outside of the boss. As a consequence, any sand particles drawn through the opening 6 on withdrawal of the nozzle, despite the wiping action of the sleeve 23, will drop into the recess 24 and be removed from the trap through the drain 25 before they can contact the adjusting threads 22.

To exclude moisture from the engaging cylindrical surfaces of the boss 8 and the collar 16, there may be provided a sealing ring 26 seating in an appropriate groove 27 in the flange-abutting face of the collar. To facilitate turning of the nozzle and the collar the outer faces of both the head 14 of the nozzle and the shoulder 17 of the collar may be hexagonal or the like in section to provide the usual flat gripping surfaces.

While normally not necessary, the construction of the nozzle assembly is such that the parts subject to the abrading action of the sand can be replaced. For this purpose, the pipe 10, as previously mentioned, is removably attached to the body of the nozzle. The other exposed part, the sleeve 23, is so positioned that it can be reached through the clean-out port 4 and removed through the central opening in the collar, should its replacement be necessary.

From the above detailed description of the invention it will be apparent that there has been provided an improved sander nozzle assembly, particularly adapted for use in sanders for locomotives and the like and of such construction that it can be attached to the air pressure line without use of external couplings. It should be understood that the described and disclosed embodiment is merely exemplary of the invention and that all modifications are intended to be included which do not depart either from the support of the invention or the scope of the appended claims.

Having described my invention, I claim:

1. In a sand trap a sander nozzle assembly comprising a seat formed in the body of said sand trap, a collar rotatably mounted in said seat, means associated with said collar for locking said collar against axial movement, and a nozzle connected to said collar and longitudinally adjustable relative to said collar and said trap body on rotation of said collar.

2. In a sand trap a sander nozzle assembly comprising a nozzle slidably received in an opening in said trap, means rotatably associated with said trap and engaging said nozzle for moving said nozzle axially relative thereto and to said trap, and means insertible in said opening and expandable therewith for locking said collar against axial movement.

3. In a sand trap a sander nozzle assembly comprising a nozzle slidably received in an opening in said trap, means rotatably associated with said trap and engaging said nozzle for axially adjusting the position of said nozzle relative thereto and to said trap means for locking said rotatable means against axial movement, and means integral with said nozzle for attaching said nozzle to an air pressure line.

4. In a sand trap in which the sand trap body is provided with an air inlet port, a nozzle adapted to be introduced into said body through

said port, a boss formed integrally with said body outwardly of said port, a collar rotatably associated with said boss and engaging said nozzle for axially adjusting said nozzle relative thereto and to said body, and means intermediate said base and bore for locking said collar against axial movement.

5. In a sand trap a sander body having an air inlet port, a circular flange formed integrally with said body and encircling the outer end of said port, a collar rotatably seated in said flange, means expansible within said flange for locking said collar against axial movement relative to said flange, and a nozzle slidably received in said port and engaging said collar, said nozzle being adjustable longitudinally relative to said body on rotation of said axially locked collar.

6. In a sand trap a body having an air inlet port, a boss formed integrally with said body and having an annular opening encircling the outer end of said port, a nozzle adapted to be introduced into said port through said opening and a collar rotatably seated in said opening for adjusting said nozzle longitudinally relative to said body, said boss having a recess intermediate said port and said opening for catching any sand drawn from said body through said port.

7. In a sand trap having an air inlet port, a nozzle adapted to be introduced into said trap through said port, a boss formed integrally with said trap outwardly of said port having an annular opening encircling the outer end of said port, a collar rotatably seated in said opening, means for locking said collar against axial movement relative to said boss, means connecting said nozzle to said collar enabling said nozzle to be moved axially on rotation of said collar and means removably seated in said port for slidably receiving said nozzle.

8. In a sand trap having an air inlet port, a nozzle insertible in said port, a boss formed on said trap outwardly of said port and having a cylindrical opening coaxial with said port, a collar rotatably seated in said opening, said collar having a shoulder adapted to abut the outer face of said boss, a resilient ring seated in a circumferential groove in said collar and adapted to engage a confronting groove formed in the inner wall of said opening, said ring and shoulder cooperating to lock said collar against axial movement, and means on said collar for engaging and moving said nozzle axially on rotation of said collar.

9. In a sand trap having an air inlet port, a nozzle insertible in said port, a boss formed on said trap outwardly of said port and having a cylindrical opening coaxial with said port, a collar rotatably seated in said opening, said collar having a shoulder adapted to abut the outer face of said boss, a split resilient ring adapted to seat and be compressed entirely within a circumferential groove formed in said collar and to engage the inner face of a confronting groove formed in the inner wall of said opening on seating of said collar, said ring when said collar is seated lying in both of said grooves and locking said collar against outer axial movement, and means on said collar for engaging and moving said nozzle axially on rotation of said collar.

10. In a sand trap having an air inlet port, a nozzle insertible in said port, a boss formed on said trap outwardly of said port and having a cylindrical opening coaxial with said port, a collar rotatably seated in said opening, said collar having a shoulder adapted to abut the outer face of said boss, resilient means associated with said collar and boss for locking said collar against axial movement and means on said collar for engaging and moving said nozzle axially on rotation of said collar.

11. In a sand trap having an air inlet port, a nozzle insertible in said port, a boss formed on said trap outwardly of said port and having an annular opening encircling the outer end of said port, a collar rotatably seated in said opening, friction spring means within said opening and associated with said collar and boss for locking said collar against axial movement and frictionally resisting rotative movement of said collar, and means on said collar for engaging and moving said nozzle axially on rotation of said collar.
